DESIGN FOR A COMBINED TURRET LATHE AND STOCK SUPPORTS

Frank S. Shields, Jamaica, N. Y.

Application April 9, 1940, Serial No. 91,560

Term of patent 14 years

To all whom it may concern:

Be it known that I, Frank S. Shields, a citizen of the United States of America, residing in the county of Queens and State of New York, have invented a new, original, and ornamental Design of a Combined Turret Lathe and Stock Supports, of which the following is a specification, reference being had to the accompanying drawing, forming a part thereof.

The figure is a perspective view of a combined turret lathe and stock supports, showing my new design.

The rear of the article, not shown, is substantially plain.

I claim:

The ornamental design for a combined turret lathe and stock supports, as shown and described.

FRANK S. SHIELDS.
